US00D797953S

(12) **United States Design Patent** (10) **Patent No.:** **US D797,953 S**
Bizzarri et al. (45) **Date of Patent:** **** Sep. 19, 2017**

(54) **RAIL ASSEMBLY**

(71) Applicant: **CPG International LLC**, Scranton, PA (US)

(72) Inventors: **Paul M. Bizzarri**, Mason, OH (US); **Chip Herr**, Columbus, OH (US); **John M. Previte**, Dublin, OH (US); **Kevin T. Burt**, Columbus, OH (US); **William G. Taylor**, Columbus, OH (US); **Matthew T. Fenneman**, Gahanna, OH (US); **Jeffrey R. Burr**, Loveland, OH (US); **Timothy C. Rothwell**, Dublin, OH (US)

(73) Assignee: **CPG International LLC**, Scranton, PA (US)

(**) Term: **14 Years**

(21) Appl. No.: **29/520,840**

(22) Filed: **Mar. 18, 2015**

Related U.S. Application Data

(63) Continuation of application No. 13/461,496, filed on May 1, 2012, now Pat. No. 9,611,650, which is a continuation of application No. 12/831,064, filed on Jul. 6, 2010, now Pat. No. 8,167,275, which is a continuation of application No. 11/292,269, filed on Nov. 30, 2005, now abandoned.

(57) **CLAIM**

The ornamental design for a rail assembly, as shown and described.

DESCRIPTION

FIG. 1 is an elevation view of a rail assembly showing our new design; and,

FIG. 2 is a perspective view of the rail assembly of FIG. 1. The broken lines in FIG. 2 indicate environment that forms no part of the claimed design.

1 Claim, 2 Drawing Sheets
